DESIGN FOR A SCREEN DOOR

Edward C. Klaiber, Memphis, Tenn., assignor to Wabash Screen Door Company, Chicago, Ill., a corporation of Minnesota

Application March 7, 1938, Serial No. 75,645

Term of patent 14 years

To all whom it may concern:

Be it known that I, Edward C. Klaiber, a citizen of the United States, residing at Memphis, in the county of Shelby, State of Tennessee, have invented a new, original, and ornamental Design for Screen Doors, of which the following is a specification, reference being had to the accompanying drawing, forming a part thereof.

In the drawing Figure 1 is a view of one side of a screen door showing my new design; Fig. 2 is a similar view of the opposite side of said door; and Fig. 3 is a horizontal cross-section on the line 3—3 of Fig. 1.

I claim:

The ornamental design for a screen door, as shown.

EDWARD C. KLAIBER.
